Attorney.

UNITED STATES PATENT OFFICE.

JUSTIN WILLIAM BARRELET, OF MARSEILLE, FRANCE.

BUCKLE ATTACHMENT.

1,279,498.

Specification of Letters Patent. Patented Sept. 24, 1918.

Application filed May 15, 1917. Serial No. 168,906.

To all whom it may concern:

Be it known that I, JUSTIN WILLIAM BARRELET, a citizen of Switzerland, residing at 123 Rue Sainte, Marseille, France, have invented new and useful Improvements in Buckle Attachments, of which the following is a specification.

My invention relates to buckles, and more particularly to an attachment therefor for securing a buckle to a strap.

An object of the invention resides in the provision of a buckle attachment of the above described character which eliminates the use of additional fastening means, such as stitching or rivets.

I will now describe one form of buckle attachment embodied in my invention, and various application of the same, and will then point out the novel features thereof 20 claimed.

In the accompanying drawings:

Figure 1 is a view showing one form of buckle attachment embodying my invention applied to a buckle;

Fig. 2 includes two views showing respectively the tongue of the buckle shown in Fig. 1, in front and side elevations;

Figs. 3 and 4 are detail views showing in front and side elevation respectively, the 30 buckle attachment shown in Fig. 1;

Fig. 5 is a view showing in front elevation the attachment and the buckle shown in Fig. 1, having applied thereto one end of a strap;

Fig. 6 is a longitudinal sectional view of Fig. 5;

Fig. 7 is a view showing a front elevation of the attachment, the buckle, and a ring, and one manner of connecting the ring to 40 the buckle by means of a strap;

Fig. 8 is a longitudinal sectional view of Fig. 7; and

Figs. 9 and 10 are views showing in reverse elevations a plurality of attachments 45 mounted upon a ring and the manner in which straps are secured to the ring by means of the attachments.

Referring to the drawings in detail and particularly to Figs. 3 and 4, C designates generally a buckle attachment which as here shown comprises a single length of rigid material such as wire or the like bent intermediate its ends to form a substantially rectangular frame L. As clearly shown in Fig. 3 the ends of the wire extend at right angles from the frame L for an appreciable dis-

tance to provide extensions M, such extensions being spaced apart in parallelism and disposed in a plane oblique to the plane of the frame L, as illustrated in Fig. 4. The 60 outer extremities of the extensions M are bent rearwardly upon themselves to provide the eyes A.

Referring now to Fig. 1, P designates one form of buckle which may be used in conjunction with the attachment C. This buckle comprises in this instance a rectangular frame N, upon which is pivotally mounted a tongue B. As shown in Fig. 2, one end of the tongue B is bent upon itself to provide 70 an eye E. The attachment L is connected to the buckle in the manner shown in Fig. 1, wherein the extensions M are pivotally connected to one side rail of the frame P by means of the eyes A. The tongue B is interposed between the eyes so that relative lateral movement of the tongue and attachment are prevented.

A practical application of the invention is shown in Figs. 5 and 6. As here shown, one 80 end of a strap G extends through the frame L, around the adjacent side rail of the frame P, and then rearwardly again to the frame L. When the strap G is under tension, the buckle and attachment assume the positions 85 shown in Fig. 6 whereby the two side rails of the frame L engage the strap laterally thus effectively securing the strap against displacement when in use. The strap G is provided with a rectangular opening F to 90 accommodate the tongue B and the eyes A and E, the tongue B extending through the opening and thus affording additional means for preventing displacement or longitudinal movement of the strap within the buckle. 95

In Figs. 7 and 8 is shown a slightly different application of the invention wherein the ring H is connected by means of the strap G to the buckle N. In this instance the attachment C is connected to the buckle 100 N in a manner identical to that shown in Figs. 5 and 6. The belt E is bent upon itself to provide a loop through which the ring H passes as is clearly shown in Fig. 8. The parallel strands of the loop are trained through the frame L of the attachment B, while the free end of the strap is passed around the adjacent side rail of the frame P and then between the parallel strands of the loop. In this manner a permanent loop is 110 formed, for retaining the ring H, in such manner that the side rails of the frame L

bear laterally against the parallel strands of the loop thereby securely holding the strap against displacement.

In Figs. 9 and 10, is shown a further application of the invention. In this instance the attachment is utilized to maintain one end of the strap in looped formation about a ring J, and without the use of the buckle. The strap is retained in looped formation in a manner identical to that shown and described with relation to Figs. 5 and 6, the ring J being the equivalent of the adjacent side rail of the frame P. This application of the invention is particularly adapted for use in the construction of harness when it is desired to interconnect a plurality of straps.

From the foregoing description taken in conjunction with accompanying drawings, it will be evident that I have provided simple and efficient means for retaining the end of a strap to the buckle or other object, and without the use of additional fastening means.

Although only one form of attachment embodying my invention is herein shown and described, it is to be understood that va-

rious changes and modifications may be made without departing from the scope of the appended claims.

What I claim is:

In combination, a buckle, an attachment comprising a rectangular frame, parallel spaced extensions formed on said frame and pivotally secured to said buckle, said extensions being disposed at an angle with relation to said frame, and a strap having one end thereof folded upon itself to provide a loop, the intermediate portion of the loop being formed with a slot, said loop being trained about the adjacent portion of the buckle and said slot receiving said extensions, the ends of the loop passing over the adjacent side portion of the frame and under the other side portion thereof.

In testimony whereof I have signed my name to this specification in the presence of two subscribing witnesses.

JUSTIN WILLIAM BARRELET.

Witnesses:

E. DUCASSON,
A. MACFARLANE.
